UNITED STATES PATENT OFFICE.

JOHN J. AULD, OF GRANITE FALLS, MINNESOTA.

VOTING MECHANISM.

Application filed August 8, 1925. Serial No. 49,072.

This invention relates to voting machines, and the general object of the invention is to provide a voting machine of a very simple character which will permit of a vote for 5 any one of a plurality of persons being cast very quickly and readily, which automatically totalizes the vote for any one person or candidate so that no time is wasted by the election officers in going over the ballots and 10 adding up the votes and no chance for mistakes are present, and which is further so constructed that only one ballot or vote may be cast for any one candidate, the mechanism being further so constructed that a 15 voter may, by simply moving the machine, bring the name of any candidate in certain voting position and vote thereon.

A further object is to provide a mechanism 20 of this kind embodying a rotatable drum upon which the names of the candidates are carried, this rotatable drum being so arranged that it may be rotated in one direction by the voter to bring the names of the candidates successively into a predetermined 25 position and which is locked from any reverse rotation, which carries means whereby an adding machine may be operated for each candidate, and which is further so constructed that when the voter leaves the booth the drum will return to its initial position ready 30 for the next voter, it being impossible for the voter to himself return the drum to this initial position or manipulate the drum otherwise than as directed.

35 A still further object is to provide a device of this character with a plurality of tally operating levers, one for each candidate, which can be brought by rotating the drum successively into position beneath the plunger, and provide a latch holding the 40 tally lever down after it has once been pressed down to register a vote until the drum has been rotated to carry the tallying lever past or beyond the operating plunger, the mechanism then releasing the tallying 45 lever so that it may be operated by a succeeding voter.

50 Other objects have to do with the details of construction and arrangement of parts as will appear more fully hereinafter.

55 My invention is illustrated in the accompanying drawings, wherein:—

Figure 1 is a side elevation of a voting machine constructed in accordance with my 60 invention;

Figure 2 is a top plan view of the structure shown in Figure 1;

Figure 3 is a fragmentary longitudinal section through the vote recording drum;

Figure 4 is a longitudinal section through 60 the vote recording drum showing the frame in section;

Figure 5 is a fragmentary section on the line 5—5 of Figure 4;

Figure 6 is a fragmentary top plan view 65 of the drum, the ends of the drum being in section;

Figure 7 is a fragmentary end view looking at one end of the drum from the inside thereof;

Figure 8 is a perspective view of the gear- 70 ing for transmitting movement to the vote registering dial.

Referring to the drawings, it will be seen 75 that I have indicated a framework composed of the uprights 10, 11 and 12 which is supposed to be disposed within a voting booth, these uprights being connected by horizontal rods 13 or other bracing means so as to form a supporting frame. The entrance to 80 this frame and the entrance to the voting booth is formed by a gate having wings 14 and 15 disposed at right angles to each other and mounted upon a rotatable pintle 16 carried by one of the posts 11 or in any other 85 suitable manner. The pintle 16 at its upper end is formed with a crank arm 17 and this in turn is connected to a rod 18.

It will be obvious now that when the voter 90 enters the booth, the rod 18 will be pushed rearward to perform a certain function to be hereinafter described, and that when the voter makes his exit from the booth the pressure upon the rod 18 will be relaxed.

Mounted within the booth, as upon the 95 horizontal members 19 and the shaft 20 carried thereby, is a drum, designated generally and as a whole 21. This drum upon one end face is formed with a rope or cable receiving groove 22, and passing over this 100 groove is a cable 23 connected to a weight 24. The purpose of this rope 23 and the weight 24 is to cause the drum to rotate in a counter-clockwise direction to an initial position and that when the voter rotates the 105 drum in a clockwise direction he winds up on this rope against the action of the weight. Also formed upon the end face of the drum are a series of ratchet teeth 25, and coacting with these ratchet teeth is a pawl 26 shown 110

as pivoted to one of the members 19, for instance, which engages with these ratchet teeth, and as long as this pawl is lowered it will prevent the retraction of the drum by the weight. The drum may be advanced in a clockwise direction so that the pawl rides over the teeth but cannot return under the action of the weight until this pawl is lifted.

10 For the purpose of lifting the pawl when the voter leaves the booth, I have illustrated a crank 27 having one arm thereof extending under the pawl and the other arm thereof operatively connected to the rod 18. Therefore, 15 it will be seen that when the voter enters the booth the rod 18 will be pushed, which will cause the crank arm 27 to lower the pawl 26 into engagement with the ratchet teeth and that when the voter leaves the booth the 20 double-winged gate moving the pintle 16 will act to lift the pawl 26 and permit the weight 24 to return the drum to its initial or original position.

The drum at one end is supported within 25 a fixed ring or cap 28 (see Figs. 2 and 3) which extends over this end of the drum and at its opposite end the drum rotates within a fixed ring or cap 29 having an opening 30 with a door 31. This door may be locked 30 closed while voting is progressing, but when the door is lifted the total vote may be read. Extending across and connecting these two caps or end members 28 and 29 are the parallel spaced wires 32. That portion 33 of 35 the drum immediately beneath these wires carries upon it the names of all the candidates arranged in any desired order, and as the drum is rotated in a clockwise direction the names of the candidates are brought beneath the wires 32 and are observable between these wires. When a name of a candidate has been brought into this position, then and only then can the voting for that candidate occur.

40 At the end of the drum opposite the cap 28 there are provided a plurality of apertures through which the tally for the vote may be observed. There is one of these perforations or observation openings 34 for 45 each of the candidates disposed immediately opposite the candidate's name, and beneath each observation opening there is located a vote register, there being as many vote registers as there are candidates, each vote register being actuated by a separate lever 35 disposed within the drum. Each lever at its end projects into a circumferential recess or groove 36 in the drum. This groove extends entirely around the drum and at one point 50 is formed as shown in Fig. 7 with a recess 36^a, having its lower and inner wall inclined outward and forward. The lever extends into the drum and is connected to a transverse shaft 37, which at its end has a crank arm 38 carrying a pawl 39. Each tallying

mechanism includes a plurality of tally wheels or registry wheels 40, each wheel carrying the numbers, for instance, from 0 to 9 or any other series of numbers and these numerals are adapted to be read through 70 the observation openings 34. The first wheel *a* of the series carries upon it the ratchet wheel 41 with which a pawl 39 on the extremity of the lever 38 operates. When the lever 35 is depressed at its outer end, 75 the pawl 39 will move the ratchet wheel 41 one step and this will move the first wheel *a* of the series one step. When this wheel *a* has made a complete revolution, it, by well-known means such as commonly found in 80 all registering mechanisms, moves the wheel *b* one step and when this wheel *b* has made its full revolution it actuates the wheel *c* one step. I have not illustrated the mechanism whereby this is secured for the reason 85 that it is common and well known and suitable registering mechanism might be used for the purpose. Each registering mechanism is preferably carried within a casing 43 and the lever oscillates through a 90 slot 44 in this casing which limits the movement of the lever.

As before stated, each lever extends out into the groove 36 formed in the fixed end of the drum and there are as many levers 95 as there are candidates. For the purpose of actuating the levers successively, I provide upon the fixed supporting ring 28 a post 45 and the plunger carrying lever 46. This lever at its outer end has a handle 47, its inner end is weighted, as at 48, and intermediate the handle and the post there is provided the plunger 49 which operates through an aperture in the ring 28, the line of movement of the plunger being radial to a 100 circle concentric to the axis of the drum. The extremity of this plunger is adapted, when the plunger is depressed, to force down the corresponding lever, thus registering a 105 vote for the candidate whose name is displayed between the transversely extending wires 32, these wires simply constituting an indicating means to indicate what candidate is being voted for. As soon as the pressure on the lever is removed, the weight 48 will 110 lift the plunger.

In order to prevent a second depression of the plunger by the same voter and a second registration of a vote for the same candidate by the same voter, I provide a latch 50 115 which, when the lever 35 is depressed, engages over the end of the lever and holds it in its depressed position until the drum has been moved any desired distance in a forward direction.

120 As soon as the drum has been moved forward so that the lever 35 escapes from beneath the head of latch 50, the lever is free to be shifted outward by the action of the inclined wall 36^a of groove 36 (see Fig. 7), 130

which will shift the pawl 39 backward so that the pawl may engage with the next tooth of ratchet wheel 41. The outer end of the lever will be held in this position against 5 any accidental tendency to swing inward by reason of the fact that the end of the lever travels in the circumferential groove 36.

For the purpose of shifting the drum any suitable handles may be applied thereto, but 10 preferably the drum will be provided close to the cap or ring 29 with a circular rail 51 which may be mounted on outstanding arms 52 extending from the drum. By this means the drum may be pulled around by the voter, 15 the pawl 26 preventing reverse movement of the drum.

The operation of this mechanism is as follows: Before the voter enters the booth the drum is turned to its initial position by 20 means of the weight and cable 23. When the voter turns the turnstile or gate composed of the members 14 and 15 he automatically lowers the pawl 26 into engagement with the ratchet teeth 25. This pawl is, of 25 course, concealed in any suitable manner so that the voter cannot lift the pawl or have access thereto. When the voter steps up to the drum, the name of the first candidate is disclosed between the wires 32. If the voter 30 desires to vote for the candidate he will depress the plunger for the first candidate and the registering lever of that first candidate will then be locked so that no second vote can be taken. He will then shift the drum one, 35 two or more steps to any desired point for the next candidate he wishes to vote for and again depress the plunger, which will register the vote for the second candidate, etc., until all the candidates for whom the voter 40 wishes to vote have been voted on. The registering mechanism for each voter, of course, will immediately register the total vote up to that time. The voter cannot turn the drum backward and, therefore, after he has voted for each candidate and turned the 45 drum to the full extent permitted by the length of the cable 23, he cannot reverse the motion of the drum and vote again and the voter then moves out of the booth. In doing so he shifts the gate through a quarter 50 of a revolution and in doing so places tension on the rod 18, which causes the lifting of the pawl 26 and the weight 24 then acts to return the drum to its initial position, as 55 before stated, ready for another voter.

It is to be understood that the cable 23 is of such length that it will permit only a full or single rotation of the drum 21 so that the voter can never turn the drum 21 more than 60 a single rotation.

It will be seen that with this construction there is no need of waiting for the vote to be counted nor any chance for the mistakes commonly found where ballots are individually counted. Immediately after the polls

close it is only necessary to open the door 31 and then rotate the drum so that the apertures 34 will come successively beneath the door and the vote may then be noted. The register will remain in the same position as long as necessary so that if there is any question as to the vote for any one candidate or the total vote the registers may be readily inspected. With this device plural voting is 70 impossible and inasmuch as there are not a plurality of buttons, keys, levers, etc., all capable of operation at the same time, there is no necessity of any interlocking system to avoid duplicate voting or plural voting. The voter can only vote for one candidate at 75 one time and the name of each candidate is brought successively beneath the wires 32 as the voter rotates the drum.

The mechanism is very simple and relatively inexpensive, cannot get out of order, 80 may be cheaply installed, and offers complete protection against fraudulent voting. Furthermore, there is no necessity with this mechanism of any officials spending from twelve to forty-eight hours in the balloting 85 place for the purpose of canvassing the ballot and this expense is done away with.

I claim:—

1. A voting machine of the character described including a rotatable drum having 90 names of the candidates arranged in circumferential series around the drum, means whereby the drum may be rotated by the voter to bring the names successively into a predetermined position, means operable by 95 the voter when a name has been brought into a predetermined position to register a vote for the candidate whose name is displayed, means permitting a movement of the drum in one direction but preventing a rotation 100 of the drum in the other direction until the voter has left the booth and then acting to return the drum to an initial position, and means for preventing a voter from operating 105 the registering mechanism more than once for the same candidate.

2. A voting machine of the character described including a booth having a gate, a drum mounted within the booth and carrying 110 the names of the candidates in circumferential series around the drum, vote registering mechanism for each candidate, actuating members mounted upon the drum, there being an actuating member for each 115 candidate and for each registering mechanism, means mounted in connection with the drum but held from rotation whereby the actuating members may be successively operated, means latching an actuating member 120 from further operation after it has been once operated, means releasing said latching means when the drum has been shifted to bring the name of another candidate into operative position and the actuating member for said candidate into operative 125 relation.

- tion to said actuating member operating means, and means put in operation when the voter enters the booth preventing the reverse movement of the drum and acting when the voter leaves the booth to release the drum but permit it to return to an initial position.
3. A voting machine of the character described including a booth having a doorway and a gate formed with right angular wings disposed in said doorway so that when one wing is at right angles to the plane of the doorway the other wing is closing the doorway and vice versa, a rotatable drum mounted within the booth and having thereon the names of candidates arranged in circumferential series, a series of registering mechanisms disposed within the drum, one for each candidate, a series of actuating members for the registering mechanisms, one for each candidate, a fixed member mounted at one end of the drum, a plunger carried by the fixed member and adapted to enter the drum and engage that actuating member which is immediately beneath the plunger, means within the drum for locking an actuating member into a depressed position after it is engaged by the plunger until the drum has rotated a predetermined amount to bring another actuating member beneath the plunger, means tending to rotate the drum to an initial position, means actuated on the opening of the gate and the entrance of the voter into the booth to prevent the rearward movement of the drum but permit its movement by the voter in one direction, and means actuated by the reverse movement of the gate upon the voter departing from the booth, freeing the drum and permitting its return to an initial position.
4. A voting mechanism of the character described including a booth, a rotatable drum mounted within the booth and carrying the names of the candidates in circumferential series, means urging the drum in one direction to an initial position, a fixed element at one end of the drum, a plunger mounted upon said fixed element, the drum having a circumferential recess in which said plunger is adapted to be forced, means holding said plunger raised, a plurality of registering mechanisms disposed within the drum, one for each candidate, an actuating member therefor connected to the registering mechanism and extending into said recess, the plunger being adapted to register with each of said actuating members in succession and depress said actuating member when the plunger is depressed, a latch holding the actuating member depressed after actuation by the plunger and until the drum has moved a predetermined amount in one direction, means carried by the drum whereby the drum may be manually rotated in one direction, a ratchet wheel mounted upon the end of the drum, a pawl coacting with the ratchet wheel and preventing reverse movement of the drum when engaged with the ratchet wheel, a gate to the booth, and means operated by the gate and upon an entrance of the voter into the booth causing the depression of said pawl into the teeth of the ratchet wheel, said means acting upon the departure of the voter from the booth to lift said pawl out of engagement with the ratchet wheel and permit the drum to be turned reversely.

In testimony whereof I hereunto affix my signature.

JOHN J. AULD.
